UNITED STATES PATENT OFFICE

WILLIAM C. CORYELL, OF YOUNGSTOWN, OHIO, ASSIGNOR TO REPUBLIC STEEL CORPORATION, OF YOUNGSTOWN, OHIO, A CORPORATION OF NEW JERSEY

TENSION CONTROL FOR ROLLING MILLS

Application filed January 8, 1930. Serial No. 419,276.

The present invention relates to tension control for rolling mills wherein tension is applied to the work as it is being acted upon by the mill and the invention consists in novel 5 apparatus for controlling such tension. The invention is in one sense related to the method of my prior patent #1,618,515 filed February 22, 1927, wherein I disclose a way of obtaining great elongations in the metal worked 10 upon with a minimum of annealings. The present invention is especially useful in carrying out the method of that patent.

One object of the present invention is to devise a control of the class described which 15 will permit of accurate and nice regulation. Another object is to produce a control which will be especially applicable to continuous mills. Other objects include ready operation 20 of the control, economy of its manufacture and maintenance, and durability and efficiency in service.

The preferred form of the invention includes working rolls, means for applying a pull to the strip to create in the outgoing 25 portion of the strip a tension which is fairly constant, retarding the ingoing end of the strip by means which will drive a generator which carries an electric load, and then adjusting the load on the generator to give an 30 accurate retarding tension in the strip on the ingoing side of the rolls. In this way I have found it possible to obtain great uniformity in tension and thereby to make it 35 possible to adjust the retarding tension to a point approaching the ultimate rupturing tension of the strip. This means that by the novel retarding means I employ I can get a maximum retarding stress. This when coupled with the forward pull on the strip gives 40 components which may be of high value for the forming of the resultants which cause the metal to flow where the tension rolling of my prior patent is employed.

Having set forth the character and nature 45 of my invention in this general way I would now call attention, for a better understanding of the same, to the following detailed description taken in connection with the accompanying drawings wherein the preferred embodiment of the invention is fully set forth.

For determination of the scope of the invention attention is directed to the appended claims.

In said drawings, Fig. 1 is a plan view of a continuous mill plant constructed and arranged in accordance with the present invention, parts of the mill being shown in section taken on a plane indicated by the line 1—1 of Fig. 4; Fig. 2 is a rear elevation of the same; Fig. 3 is a vertical section through one of the mill couplings and gearings, the plane of section being indicated by the line 3—3 of Fig. 1; Fig. 4 is a side elevation of the plant arrangement of Fig. 1; Fig. 5 is an elevation of gearing through which energy is transmitted to the electric generator of the plant, parts being shown in section taken on a plane indicated by the line 5—5 of Fig. 1; Fig. 6 is a diagram of the mechanism of Fig. 1 illustrating the electrical connections; and Fig. 7 is a diagram of a strip mill plant showing additional control rolls and a modified pulling device. Throughout these views like characters refer to like parts.

Referring to the drawings in detail, A designates a strip of metal passing through mills B and C and being wound upon a reel D. The latter serves as a pulling device to place tension in the strip. The retarding or power-consuming mechanism is the electric generator G with its loaded circuit F. The pulling device D is here shown driven by an electric motor M. In the mill plant of Fig. 7 the reel D is replaced by a pulling machine H of somewhat different construction.

Although the work upon which the mill operates is shown as a metal strip A, it will be understood that the work might consist of metal pieces of other shapes and kinds. In such instances the pulling devices D and H might have to be replaced by other pulling devices. This would be so if the work were not flexible enough to bend around the drums of the devices D and H. Of course, it is to be understood, with heavy work these drums may be given large diameters. Although there is the possibility of a wide range of variation in the work upon which the reels act, yet for the purposes of the present disclosure I have chosen to illustrate my invention in connec- 100

tion with metal strip as the material worked upon and I have designed the illustrated mechanism for handling that material.

The mills B and C are similar in construction and consequently the description of one will apply to both. Thus, in mill B, 10 and 11 designate the housings whose feet 12 and 13 rest upon the shoes of 14 and 15 extending transversely of the direction of travel of strip 19. A. The housings may be of any desired construction and are provided with the usual windows 16 in which are located lower boxes 17 and upper boxes 19. Breakers 18 bear upon the upper boxes 19. These boxes provide bearings for the lower roll 20 and the upper roll 21. In the present mill the rolls 20 and 21 are backing-up rolls of large diameter for reducing rolls 22 and 23 of small diameter. The latter are offset from the vertical plane 23 through the axes of the rolls 20 and 21. This offset roll construction constitutes the subject matter of my application Serial No. 309,531, filed October 1, 1928. The bearings for the reducing rolls 22 and 23 are provided by boxes 24 and 25 carried in any suitable way by the housings 10 and 11. Each housing is provided with an adjusting screw 26 which forms the screw-down mechanism of the mill. The lower ends of these screws press 30 upon the breakers 18. Any suitable screw-down mechanism may be used on these mills. Suitable counter balances for the rolls will also be employed, but these are well known and need not be illustrated. Reference may 35 be had to my prior Patent No. 1,233,647, dated July 17, 1917, for an example.

In the case of mill C the shoes 14^a and 15^a upon which the feet 12 and 13 rest are shorter than the corresponding shoes 14 and 15 upon 40 which the feet 12 and 13 of mill B rest. The latter mill is the one which is connected up to the retarding or power-consuming generator G, and consequently the same shoes are used for supporting the feet 27 and 28 of a 45 gear casing 29 containing the gear wheels 30 and 31 and intended for transmission of power from the rolls of mill B to the generator G. Gear wheel 30 is keyed to a shaft 32 which is journaled at its ends in suitable bearings 50 in the walls of the casing 29. Similarly, gear wheel 31 is keyed to a shaft 33 which has its ends journaled in bearings in the same walls of the casing and, in the instance shown, in the same vertical plane as the shaft 32. The adjacent neck 34 of roll 21 of mill B is 55 coupled to the end of shaft 32 by means of a coupling shaft 35 and sliding couplers 36. In the same way the neck 37 of roll 20 of mill B is coupled to the end of shaft 38 and sliding couplers 39. As a means of support, the coupling shaft 38 has a central cylindrical portion 40 which bears upon a block 41 carried by a frame member 42, at the upper end of box 43 resting upon a suitable support. 60 To extend this supporting force to the upper

coupling shaft 33, I provide the latter shaft with a central cylindrical portion 44 which rests upon a block 45 carried by member 46 resting upon a block 47 which bears upon the upper portion of the cylindrical bearing surface 40 of the lower coupling shaft 38. The gear wheels 30 and 31 mesh with each other and consequently there is no slippage between the rolls 20 and 21 of the mill. 70

The end of shaft 33 distant from the mill B is provided with a coupling head 48 and this head fits the head of the coupler 49 and the latter at its opposite ends fits a coupling head 50 upon the adjacent end of shaft 51 which carries gear wheel 52 which meshes with pinion 53 mounted upon shaft 54 in line with generator shaft 62. The shafts 51 and 54 are journaled at their opposite ends in bearings 55 and 56, respectively, formed in webs 57 and 58 of a supporting casting 59. The latter is independent of the shoes 14 and 15, but obviously may be mounted upon any suitable support such as the floor 60 upon which the shoes 14 and 15 are located. The end of the shaft 54 which is distant from the mill B is connected by coupling 61 to the end of the shaft 62 of the rotor of the generator G. The parts of the generator are suitably supported upon a base 63, the shaft 62 having bearings 64 and 65 extending upward 80 from the base. The generator structure may be varied a great deal in form and there seems to be no necessity of describing any particular generator in detail. The base 63 may rest upon any suitable elevation of the floor 60 which is shown stepped, with portions suited in elevation to the mechanisms installed. 90

The reel D is one device which may be employed for giving tension to the strip A. When employed it must be, of course, positively driven. In the embodiment shown, this is accomplished by an electric motor M and a gear train including pinion 66 and gear wheel 67. The reel D comprises a drum 68 mounted upon a shaft 69 to which reel 67 105 is keyed. The drum 68 is provided with some means for attaching the end of the strip. Such means are well known and as the same in itself forms no part of the present invention, it seems unnecessary to illustrate any means of attachment. Ordinarily, a slit of some kind is provided into which the end of the strip is inserted. Many such reels are on the market and available to those who would practice the present invention. The shaft 69 upon which the drum 68 is mounted is journaled in suitable bearings 70 and 72. The former is found in the upper portion of a pedestal 71 mounted upon the floor 60 as are the other various supports. The latter is 110 similarly found in and supported by a pedestal 73, also located upon the floor 60. The pedestal 73 also provides a bearing 74 for the pinion shaft 75 to which the pinion 66 is keyed. A bearing 76 is a mate to the bear- 115

120
125
130

ing 74 but is mounted upon a separate support 77 also adapted to rest upon the floor 60. The shaft 75 extends some distance beyond the bearing 74 toward the shaft 78 of 5 the motor M. The shafts 75 and 78 are in alignment and joined by a coupling 79. Motor shaft 78 finds its support in bearings 80 and 81 mounted respectively upon pedestals 82 and 83 rising from a base 84. The latter, 10 as with the other pieces of apparatus, rests upon the floor 60. The motor M, like the generator G, is of well-known construction and need not be described in detail.

The general arrangement of the mill plant 15 thus far described is diagrammatically illustrated in Fig. 6. There some of the parts are omitted for clearness, but the general arrangement will be readily understood. The generator G, which forms the retarding 20 mechanism has its terminals 85 and 86 connected to a loaded circuit F comprising conductors 87 and 88 which lead respectively from said terminals 85 and 86, the one to the terminals of a series of electric lamps 89 25 and the other to the movable arm 90 of a rheostat R. The several contacts 91 of the rheostat are connected at intervals to the turns of a resistance winding 92. The connections are in series so that as the arm 90 is 30 moved to the left, as seen in Fig. 6, the resistance in circuit is cut down, and when moved to the right the resistance in circuit is increased. The left-hand contact 91 is connected by conductor 93 to the other terminals 35 of the lamps 89. Thus we have a simple loaded electrical circuit wherein the lamps 89 are a steady load and the rheostat R provides a variable load.

The motor M which drives the pulling 40 device D has its terminals 94 and 95 connected by conductors 96 and 97, respectively, to supply means 98 and 99 leading from a suitable source of supply of electricity. The motor M, like the generator G, may vary 45 considerably in construction. There are many motors and generators at present on the market which will serve the purpose required by the present invention.

In operation the strip is threaded between 50 the reducing rolls of the mills B and C and has its end secured to the drum 68 of the pulling device D. The motor M is started and a pull is exerted upon the strip A in the direction of the arrows. The tension thus 55 applied causes the reducing rolls 22 and 23 of each of the mills B and C to press against the strip to apply rolling pressure, and thus reduce the thickness of the strip, flatten it, or otherwise treat it according to the position 60 of the backing-up rolls 20 and 21. The position of the latter is determined by the positions of the screw-down screws 26. In the instance shown, the mill C is not connected to any driving source but the required 65 reduction pressure is obtained through the

screw-down and the action of the offset rolls against the large diameter backing-up rolls in response to the pull of the strip. The same is true of the rolls of mill B, but in the latter case the rolls are connected to the retarding 70 electric generator G, and that generator is driven by the rotation of the backing-up rolls 20 and 21.

As the strip A is advancing, the small diameter rolls 22 and 23 are rotated by the frictional contact of the strip with the rolls, and then the small diameter rolls by frictional contact with the backing-up rolls rotate the latter. The rotation of the backing-up rolls is communicated to the gearing through the 75 rotor of the generator G. The action of the rotor is resisted by the load upon the external circuit including rheostat R and lamps 89. When contact 90 is in engagement with the left-hand contact 91, as the parts are viewed 80 in Fig. 6, there is a constant load upon the circuit. That load is produced by lamps 89. This constant load will exert some retardation upon the connected gearing and rolls, and consequently there will be exerted by 85 the mill B a retardation upon the advance movement of the strip A. Where the motor M is a constant torque motor, the pull of the pulling device D will not be lessened by 90 this retardation caused by the mill B, but 95 the effect will be to increase the tension in the strip A over that which is produced by the pulling device D when acting alone.

It is apparent that the retarding effect 100 produced by the steady load of the lamps 89 may have its application to the strip A varied by the screw-down mechanism of the mill B. Such mechanism might be loosened up to the point where the strip A would, 105 through slippage, fail to drive the generator G. But it should be understood that the screw-down mechanism should be adjusted so that there will be no slippage between the strip A and the rolls 22 and 23 on the one hand, or between the rolls 22 and 23 and the 110 rolls 20 and 21 on the other hand. Thus with the steady load upon the generator circuit, a tension is produced in the strip A which is the result of tension applied by the 115 pulling device D and an opposing tension applied by the mill B. The constant load may be determined within desired limits by the number of lamps 89 included in circuit. The effect of this is to similarly determine roughly the tension in the strip A. For refinements in adjustment of the tension in the strip the rheostat R will be used. By shifting its arm 90 back and forth over its 120 contacts 91 the load on the generator circuit will be varied, and accordingly the resistance offered to the rotor of the generator will be varied, and this variation will be communicated to the gearing through the rolls of mill B. Thus, by a deft handling 125 of the rheostat arm 90 it will be possible to 130

obtain sufficiently refined tension adjustments. Workmen with the apparatus will soon acquire the ability to obtain nice results with different kinds of work.

5 Instead of employing a reel for the pulling device, I may prefer in some installations to employ a pulling machine such as the machine H diagrammatically illustrated in Fig. 7. The use of such a pulling machine will allow the strip or other work to pass continuously through the plant from one end to the other. In other words, the pulling machine provides for a continuous straightaway operation of the material being acted upon. In this diagram the strip first passes between rolls L which may be pinch rolls or the rolls of a small mill. These engage the work and pass it along toward the mill B. After passing through the mills 20 B and C the strip A travels around the drums 100, 101, 102, and 103 of the pulling machine H. After leaving the drum 103 the strip passes between rolls N which are the last to act upon the strip. The pulling machine H 25 has its drums individually driven, and these drums act like capstans to pull upon the strip by frictional engagement with it. To insure proper friction, the rolls N must be positively driven to exert a slight pull upon 30 the strip leaving the last drum 103 of the pulling machine. It is believed that this pulling machine need not be further described, as a full description and illustration of the same will be found in my prior application, Serial No. 280,681, filed May 26, 1928.

In carrying out my invention it will be apparent that certain alterations may be made in the mechanisms and arrangements illustrated without departing from the spirit 40 and scope of the invention. Thus, the lamps 89 in the circuit F might be replaced by other energy consuming devices. Again, as indicated, different pulling devices might be employed to take the place of the reel D and 45 pulling mechanism H. Likewise, different types of mills might be employed. Other changes will also suggest themselves to persons skilled in the art. I, therefore, do not wish to be limited to the specific mechanisms 50 and arrangements shown, but aim to cover by the terms of the claims all such alterations and modifications as rightly come within the spirit and scope of my invention.

What I claim as new and desire to secure 55 by a patent of the United States is:

1. In a cold rolling strip mill, working rolls for engaging and operating upon the strip as it passes between them, means co-operating with said rolls to produce a high 60 substantially constant tension in the outgoing portion of the strip, means for restraining the ingoing portion of the strip, a loaded electric generator driven by said restraining means and operative through the latter to exert an even retarding tension in the ingoing

portion of the strip, and means for regulating the load on said generator to nicely adjust the retarding tension in said strip, whereby the retarding tension in the strip may be raised to, and maintained in, proximity to the ultimate rupturing tension of the strip. 70

2. In a cold rolling strip mill, main working rolls for engaging and operating upon the strip as it passes between them, means for applying a high substantially constant pull upon the strip on the outgoing side of said main rolls, auxiliary rolls for engaging and retarding the strip on the ingoing side of said main rolls, a loaded electric generator driven by energy derived from said auxiliary rolls and operative through the latter to exert an even retarded tension in the strip on the ingoing side of said main rolls, and means for regulating the load on said generator to nicely adjust the retarding tension on the ingoing side of said main rolls, whereby the retarded tension in the strip may be raised to, and maintained in, proximity to the ultimate rupturing tension of the strip. 80 85

In witness whereof, I hereunto subscribe 90 my name this 4th day of Jan., A. D. 1930.

WILLIAM C. CORYELL.
